UNITED STATES PATENT OFFICE.

GEORGE H. PHILLIPS, OF MUSKEGON, MICHIGAN.

CARRIER ATTACHMENT FOR AUTO RUNNING-BOARDS.

1,295,923.

Specification of Letters Patent.

Patented Mar. 4, 1919.

Application filed August 27, 1913. Serial No. 251,680.

To all whom it may concern:

Be it known that I, GEORGE H. PHILLIPS, a citizen of the United States, residing at Muskegon, in the county of Muskegon and State of Michigan, have invented certain new and useful Improvements in Carrier Attachments for Auto Running-Boards, of which the following is a specification.

This invention relates to package and article carriers, and more especially to such as are adapted to be mounted on a vehicle; and the object of the same is to produce a carrier for attachment to the running board of an automobile.

15 The invention comprises a light structure, preferably of screen wire, and including a main or body panel and two end panels, the former hingedly connected with the outer edge of the running board and the 20 end panels hingedly connecting with the extremities of the main panel. Further details will be found in the following description and claims, and attention is invited to the drawings, wherein—

25 Figure 1 is a side elevation, and

Fig. 2 a plan view showing this carrier applied to the running board of an automobile between its front and rear fenders.

Fig. 3 is a transverse section on the line 20 3—3 of Fig. 1 and

Fig. 4 is a similar section with the part folded.

Fig. 5 is a side elevation of the folded carrier.

35 In the drawings the automobile body A has doors D and front and rear fenders F and R, as usual between which latter extends the running board B, the same running from a point adjacent the front fender, 40 past both doors, to a point adjacent the rear fender. This is the place where suit cases, boxes, and the like are usually carried by motorists when making a tour, although naturally whatever they mount on the running board at this point must be strapped or otherwise fastened against dislodgment due to the vibration in passing over rough roads. The running board is used in getting in or out of the vehicle, but this convenience is sacrificed when packages are 45 carried thereon. I propose to mount on the running board between its fenders, a foldable carrier, which when folded will not destroy the ordinary use of the running

board, and when distended will produce a 55 good sized receptacle for packages and other articles.

Coming now to the details of the present invention, the numeral 1 designates the main panel of this carrier which may well be a 60 frame wherein is wire screening, as shown in Fig. 1, and the numerals 2 designate the end panels similarly made and hinged at 3 to the extremities of the main panel by any means which will permit them to close 65 against the same as seen in Fig. 5. 4 are braces whereof there are two, one for each end panel hinged at 5 to the inner edge of such panel 2 as shown in Fig. 3, and each brace has a hook 6 at its outer end for engaging over the upper bar of the main panel when the end panels are stood upright, as shown. The length of the main panel is substantially the same as the distance between the fenders F and R, and the 70 length of the end panels is the width of the running board B. In fastening these parts to the running board, I make use of two or more hinges 7, each having its upper leaf secured to the main panel 1 or the frame 75 bar thereof, and its lower leaf carried downward and hooked as at 8 around the bead 9 which is usually formed along the edge of the running board B. This leaf is secured thereto by screws, nails, bolts, or possibly set screws as indicated at 10 in Fig. 80 4, and these set screws may have wing-shaped ends so that they become in effect thumb screws and need no tools for operation. Thus the carrier can be attached to 85 and detached from the running board by hand and with but a moment's time. When folded it assumes the position shown in Fig. 5, and if it is quite stout it is not materially injured if the operator steps upon it 90 in passing into the vehicle or out of the same. Also, being of wire screen, any dirt left by the foot will drop through the wire screen onto the running board. When it is used the main panel is raised and the end panels 95 swung to the position shown in Fig. 2 and the braces swung on their hinges so that their hooks engage the upper edge of the main panel as best seen in Figs. 1 and 2; and thereafter packages may be stored 100 within the carrier and need not be strapped or otherwise fastened to the machine when taking long tours. I prefer that the device 105

be made entirely of metal, and it should be galvanized, or otherwise treated to prevent rust.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent is:—

- 15 1. In a carrier for the running boards of automobiles, the combination with a main panel, two end panels, hinges connecting these panels with the extremities of the main 20 panel, and for each end panel a brace hinged at one end to the free end of the end panel and having a hook at its other end; of means for hingedly mounting the lower edge of the main panel on the outer edge of the 25 running board of the machine.
2. In a carrier for the running boards of automobiles, the combination with a main panel composed of a frame and a screen filling, end panels composed of a frame and 30 a screen filling, hinges connecting these

panels with the extremities of the main panel, and for each end panel a brace hinged at one end to the free end of the end panel and having a hook at its other end; of means for hingedly mounting the lower 35 frame bar of the main panel on the outer edge of the running board of the machine.

3. In a carrier for the running boards of automobiles, the combination with a main panel composed of a frame and a screen 40 filling, end panels composed of a frame and a screen filling, hinges connecting these panels with the extremities of the main panel, and for each end panel a brace hinged at one end to the free end of the end 45 panel and having a hook at its other end; of a plurality of hinges each having its upper leaf connected with the lower frame bar of the main panel and its lower leaf hooked around the bend at the outer edge of the 50 running board, and a set screw through said leaf against said bend, for the purpose set forth.

In testimony whereof I affix my signature in presence of two witnesses.

GEORGE H. PHILLIPS.
